HOUSE

Dwight L. Brown, Barbourville, Ky. 40906

Filed July 28, 1967, Ser. No. 8,048

Term of patent 14 years

(Cl. D13—1)

Fig. 1

Fig. 2

For convenience of illustration only parts of the brick surfaces and the shingle roof have been shown in the several views of the drawings. It is understood that these surfaces continue throughout the plain areas shown.

I claim:

The ornamental design for a house, as shown and described.
